(57) **CLAIM**

The ornamental design for a miniature microphone housing and switch, as shown and described.

DESCRIPTION

FIG. 1 is a perspective view of a miniature microphone housing and switch showing our new design;

FIG. 2 is a right side view thereof;

FIG. 3 is a front view thereof;

FIG. 4 is a left side view thereof;

FIG. 5 is a rear view thereof;

FIG. 6 is a top view thereof;

FIG. 7 is a bottom view thereof;

FIG. 8 is a perspective view of an alternative embodiment;

FIG. 9 is a right side view of the embodiment of FIG. 8;

FIG. 10 is a front view of the embodiment of FIG. 8;

FIG. 11 is a left side view of the embodiment of FIG. 8;

FIG. 12 is a rear view of the embodiment of FIG. 8;

FIG. 13 is a top view of the embodiment of FIG. 8; and,

FIG. 14 is a bottom view of the embodiment of FIG. 8.
